(57) **CLAIM**

The ornamental design for a combined mango slicer and peeler, as shown and described.

DESCRIPTION

FIG. 1 is a perspective view of a combined mango slicer and peeler according to our new design.

FIG. 2 is a front elevation view thereof; the rear elevation view is a mirror image of FIG. 2.

FIG. 3 is a right side elevation view thereof; the left side elevation view is a mirror image of FIG. 3.

FIG. 4 is a top plan view thereof; and,

FIG. 5 is a bottom plan view thereof.

The broken lines in the figures form no part of the claimed design.

1 Claim, 4 Drawing Sheets
